UNITED STATES PATENT OFFICE.

JERE VAN RENNSELAER, JR., OF COUNCIL BLUFFS, IOWA.

ELECTRIC HAND LANTERN.

Application filed April 13, 1922. Serial No. 552,343.

My invention relates to hand lanterns suitable for use by railway trainmen and others engaged in occupations where it is desirable that the lantern be capable of use for signaling as well as for illumination in the immediate vicinity of the user. It is the object of my invention to provide an electric hand lantern which may be used and carried by trainmen without interference with the free use of both hands, and which is so carried that lantern-signals may be given by moving the hand in the usual way. A further object of my invention is to provide a simple and convenient means for attaching a small electric lamp upon the back of the hand or wrist, and for suitably guarding the same against accidental breakage. A further object of my invention is to provide a detachable reflector usable in connection with the guarding means for the electric lamp, whereby to direct light from the lamp upon a book, paper, or the like, while the hand is positioned for writing thereon.

In the accompanying drawings, Fig. 1 is a perspective view of a hand lantern equipment embodying my invention, Fig. 2 is a plan view of the lamp-holder and guard as arranged for lacing to a glove or hand-covering, Fig. 3 is a plan view of the same provided with attaching-straps for use generally or upon the bare hand, and Fig. 4 is a longitudinal section on the line 4—4 of Fig. 3.

In carrying out my invention I provide a battery capable of supplying the required electrical energy for the lamp or lantern, and removably dispose said battery in a suitable casing 5 which is adapted to be carried upon the body of the user, preferably being attached to a belt 6 which is worn about the waist beneath the coat or outer garment. To the battery terminals is connected a lamp-cord or two-wire flexible conductor 7, the same being of sufficient length to extend from the casing 5 to the arm-pit of the user, and thence through the sleeve to the wrist, as indicated in Fig. 1. At the wrist-end of the cord 7 is carried the plug 8, comprising an insulating body through which the conducting terminals extend, and which is adapted for detachable connection with the mating terminal-plug of the lantern.

In the preferred construction of the lantern, I employ a small electric lamp 9 of which the base 10 is screwed into a socket 11 mounted upon a holder formed by two sheets or pieces 12 and 13, of flexible material such

as leather, the edges of the sheets being secured to each other by stitching 14. The bottom or closed end of the lamp-socket is secured to a plate 15 disposed between the sheets 12 and 13, the upper portion of the socket projecting through an opening therefor in the upper sheet 12. In the structure represented in Figs. 3 and 4, the holder is provided with straps 16 and 17 by which it is attached to the hand of the user, the strap 16 passing across the palm adjacent to the first joints of the fingers, and the strap 17 passing around the wrist. The lamp is positioned approximately in transverse alignment with the strap 16, so as to extend out from the back of the hand adjacent to the knuckles. At the rear or wrist-end of the holder, the sheet 12 is swelled upwardly to form a pocket for the terminal-piece or plug-socket 18 with which the cord-plug 8 is detachably connected. Preferably a small hook 19 is provided on the plug 8 for engagement with a pin 20 on the holder, as shown in Fig. 3, to prevent accidental disengagement of the plug from its socket. From the plug-socket 18 a wire 21 is extended through the holder between the sheets 12 and 13 directly to the lamp-socket, and another wire, 22, is extended to the lamp-socket by way of a switch 23, as represented by dotted lines in Fig. 3. The switch is operated, to close or open the lamp-circuit, by means of a small knob or button 24 which extends through the upper sheet 12 of the holder, as shown. Upon the back of the holder, concentric with the lamp-socket, the base-ring 25 of the guard is secured by means of small screws 26. To said base-ring are secured the ends of two U-shaped guard-rods 27 which cross each other at right angles, straddling over the lamp, as shown. The guard-rods cross from side to side diagonally of the longitudinal axis of the holder, to facilitate connection therewith of the reflector 28. The outer portion of the reflector is a sphero-segmental shell which fits over the rounded outer portions of the guard-rods, and merges with the inner cylindro-segmental portion, the latter extending around the leg-portions of the guard-rods and resting against the base-ring 25. Adjoining the base-ring, at the open side of the reflector, are two fingers 29 which terminate in hooks engaging the legs of the guard-rods, as shown.

At one or more points on the guard-ring there is provided a resilient

tongue or latch-piece 30 which is adapted to engage a small perforation or indentation in the reflector, whereby to retain the latter against accidental dislodgment. When it is 5 not desired to use the reflector, the same is readily removed by first releasing the latch-tongue and then pulling the reflector straight out from the guard. When replacing the reflector upon the guard, the latch 10 will engage automatically as the bottom edge of the reflector is seated upon the base-ring.

In the modified form of the holder shown 15 in Fig. 2, the attaching-straps 16 and 17 are omitted, and a number of perforations 31 are formed in the edge-portions of the holder. This form of the holder is intended 20 for attachment to a glove or mitt, by means of lacing passed through the perforations, the hand-covering being worn whenever the lantern is to be used.

From the foregoing it will be apparent 25 that my invention provides a simple and convenient electric lantern, especially adapted for use by railway trainmen, because of the fact that it permits free use of both hands, and also enables the usual lantern-signals to be given by the movements of the hand customarily and habitually employed 30 by trainmen. For general use the reflector may be removed so that the light may be

cast in all directions. The reflector is especially serviceable, however, for conductors, inspectors, car-checkers, and others whose duties require the use of the hand in writing or making entries or notations in books or upon papers, the lamp and reflector being so arranged that the light is thrown thereby directly upon the book or paper at and around the point thereon touched by a pencil or the like held in the hand on which the lantern is mounted. It will be obvious, of course, that the lantern may be advantageously used in various occupations, and that its use in railway service is emphasized 40 merely because of its special utility and adaptability for such purposes.

Now, having described my invention, what I claim and desire to secure by Letters Patent is:

An electric hand lantern, comprising an electric lamp, a support member therefor, guard members positioned in said support member and surrounding said lamp, a removable deflector member, and means for tensioning said deflector member upon the guard members, including a fashioning of the deflector to engage the guard members, and a clasp for additionally holding said deflector in its tensioned position.

JERE VAN RENSSELAER, JR.
